UNITED STATES PATENT OFFICE

JOHN E. CASTER, OF CINCINNATI, OHIO, ASSIGNOR TO CINCINNATI GRINDERS INCORPORATED, OF CINCINNATI, OHIO, A CORPORATION OF OHIO

GRINDING MACHINERY

Application filed September 16, 1927. Serial No. 220,023.

This invention relates to improvements in grinding machinery and has particular reference to what is commonly termed a centerless grinder.

6 A machine of this type as at present known to the art normally comprises a pair of spaced wheels which grind and rotate the work and an intermediate rest which supports the work during the grinding 10 operation.

For the grinding of many articles it is desirable to vary the separation of the wheels or as it is termed the width of the grinding throat. This has hitherto been accomplished 15 through the use of a sliding carriage or the like, in conjunction with means for shifting the carriage back and forth. This has meant the shifting of a large weight with attendant friction and retardence of rapid action.

20 One of the objects therefore of the present invention is the provision of a novel and improved mechanism for facilitating the ready variance of width of grinding throat in a centerless grinder.

25 A further object of the present invention is the provision of a mechanism for varying the grinding throat which will to a maximum degree eliminate the frictional retardences or the like experienced with previously 30 known structures and the resistance due to inertia of the mass of the unit to be shifted and which will on the contrary utilize the weight of the parts in initiating and effecting certain of the shifting movements.

35 Another object of the invention is the simplification of drive mechanism for the shiftable unit to insure constant operation thereof while permitting ready adjustment for either sizing or throat adjustment during 40 grinding.

Other objects and advantages of the present invention should be readily apparent by reference to the following specification taken in connection with the accompanying drawings, and it will be understood that I may make any modifications in the specific structural details hereinafter disclosed within the scope of the appended claims, without departing from or exceeding the spirit of the 45 invention.

Figure 1 is a front elevation of a machine embodying these improvements.

Figure 2 is an end view thereof.

Figure 3 is a sectional view of the control cam and associate parts. 55

Figure 4 is a vertical section illustrating the control cam drive mechanism, and

Figure 5 is a detail of the belt drive connections to the shiftable unit. 60

In the drawings the numeral 10 designates the bed of a centerless grinder having supported thereon the spindle 11 for the grinding wheel 12 which is operated at a high or grinding rate of speed and rotated in a clockwise direction as viewed in Figure 1. 65

This grinding wheel may be suitably driven as from the motor or other source of power 13 attached to the bed and through belt 14 and belt 15 from pulley on shaft 16.

The bed is formed with the guide 17 for 70 slide 18 which is movable toward and from the grinding wheel spindle by means of a suitable adjusting screw operated by the hand wheel 19. This slide is formed at its inner end with the ways 20 adjustably supporting the sliding base 21 of the work rest bracket 22 having a work rest blade 23 projecting adjacent the face of the grinding wheel 12 and adapted to support a work piece 24 in engagement therewith as particularly illustrated in Figure 3. It will thus be noted that the slide 18 may be given a back and forth movement for adjustment purposes and that additionally the supplemental slide 21 may be adjusted with respect to the main slide to suitably vary the position of the work rest blade with respect to the grinding wheel for various adjustments of the regulating wheel slide. 75 80 85

The regulating wheel slide is in turn provided with the bearing portions 25 for the trunnions 26 of the regulating wheel unit 27. This unit has journalled therein the spindle 28 for the regulating wheel 29, said spindle being supported at a transverse angle to the 90 general plane of the machine, whereby the regulating wheel is held in permanent tilted relation exerting a feed component against the work which will tend to urge the work through the machine. In order that the 95 100

regulating wheel may have proper line contact with a work piece 24 on the work rest 23 the unit 27 is provided with the ways 30 in proper angular relationship to the regulating wheel spindle. Slidable on these ways 5 is the truing fixture 31 which will thus produce on the surface of the regulating wheel a contour such that it will constantly present a line contact to the work piece parallel to the face of the grinding wheel under normal 10 conditions. It will of course be understood that if desired different truing mechanism or control therefor may be substituted permitting from truing of the regulating wheel.

15 In centerless grinding there are two well recognized methods of producing work, one of which is known as the through feed method in which the work progresses axially along the work rest through the grinding 20 throat and which is suitable for ordinary cylindrical work.

25 The other method is that in which the work piece is suitably introduced between the wheels and the width of the grinding throat or space between the wheels is varied to progressively reduce the diameter of the work piece. This method is particularly applicable in the case of form grinding or preparation of specially shaped work pieces.

30 The present structure is capable of use for either method of grinding but is particularly designed for the infeed method. As has been mentioned the regulating wheel unit 27 is pivoted by trunnions 26 to slide 18, 35 the weight of the unit being disposed outwardly of the trunnions as respects the grinding throat.

35 By reference to Figure 3 it will be at once apparent that oscillation of the unit 27 about trunnions 26 will vary the space between the grinding wheel 12 and regulating wheel 29. To effect such oscillation use is made of the shaft 32 suitably journaled on slide 18. This shaft is provided with a worm gear 33 meshing with worm 34 on shaft 35. This 45 shaft is coupled by belt 26 with drive pulley 37 on the suitably actuated shaft 38 operated from a suitable source of power.

40 Shaft 32 has removably mounted thereon 50 on the interchangeable cam 39 which bears against the antifriction roller 40 at the lower end of slide plunger 41. This plunger is movable in passage 42 of unit 27 being adjustable by screw 43 and hand wheel 55 44. A suitable graduated dial 45 serves to indicate the effect of adjustment thereof.

55 By reference to Figure 3 it will be noted that the structure just described forms in effect a bell crank or L lever type of mechanism in which the spindle for the regulating wheel is carried by one end of the lever and a cam member serves to engage and lift the opposite end of the lever about the vertex of the angle as a fulcrum or 60 pivot. It will likewise be noted that the

balance of weight of the associate parts is such that the contact roller on the unit is at all times pressed by the weight of the parts against the cam tending to swing the parts backward and increase the separation 70 between regulating wheel and grinding wheel. Consequently, in place of having to overcome the inertia of mass of the parts each time that it is desired to decrease and each time that it is desired to increase the weight of the grinding throat it will be seen that the parts are balanced on a satisfactory supporting pivot as distinguished from a frictional slide and also that they are so mounted that the weight of the parts 75 automatically moves them into releasing position to whatever extent such movement is permitted by the contour of the rotating control cam.

80 In order that the regulating wheel may be suitably driven or rotated without the necessity of placing the driving motor therefor directly upon the movable unit as has been considered necessary in the past, an improved drive connection is provided 85 from the base. This includes a prime shaft 46 which may be driven by a belt 47 from shaft 16 or otherwise as desired. Supported for pivotal movement about shaft 46 as a center is the arm 48 supporting a second shaft 49 and belt tensioning arm 50. Shafts 46 and 49 are respectively provided 90 with pulleys 51 and 52 connected by drive belt 53 so that shaft 49 is driven by shaft 46 but capable of swinging movement relative thereto. Arm 50 is adjustably connected as by the eccentric 54 with the regulating wheel unit 27. Rotation of the eccentric and locking in adjusted rotated position therefor serves to vary the position 95 between the centers of shaft 49 and spindle 28 of the regulating wheel to adjust the tension of drive belt 55 which has been indicated as of the multiple type such as employed in the texrope drive for example.

100 It will thus be noted that shaft 49 is capable of in and out movement to correspond to adjustment of slide 18 on its ways without interference with the drive, while the combined swinging of arm 48 and arm 105 50 about the eccentric 54 permits of tilting or oscillation of unit 27 about its trunnion or pivot center 26 without appreciably effecting the tension of the drive connections 55. Consequently, any desired adjustment 110 may be given either to the complete regulating wheel mechanism or to the pivotally supported unit without disturbing the drive of the parts.

115 It will be understood that the machine 120 in question is intended to function in accordance with general centerless grinder principles and that ordinary mechanism feed, automatic ejection and the like may be 125 employed in conjunction therewith. To fa- 130

cilitate this automatic operation shaft 32 is provided with bevel gear 56 meshing with gear 57 on shaft 58 which extends toward the front of the machine and may be coupled to suitably drive automatic feed or ejection or other mechanisms as desired.

I claim:—

1. A centerless grinder including a bed, ways on the bed, opposed grinding and regulating wheels carried by the bed, the grinding and regulating wheels having a grinding throat between them, means for rotatably supporting the grinding wheel in a fixed position on the bed, a slide on the ways of the bed, a regulating wheel unit pivotally supported on the slide, a plunger adjustably reciprocatable through the regulating wheel unit, and a cam rotatably carried by the slide and adapted to engage the plunger for raising and lowering the regulating wheel unit about its pivot and urging the regulating wheel toward and from the grinding wheel to vary the grinding throat.

2. A centerless grinder including a bed, ways on the bed, opposed grinding and regulating wheels carried by the bed, the grinding and regulating wheels having a grinding throat between them, means for rotatably supporting the grinding wheel in a fixed position on the bed, a slide on the ways of the bed, a regulating wheel unit pivotally supported on the slide, a plunger adjustably reciprocatable through the regulating wheel unit, and a cam rotatably carried by the slide adapted to engage the plunger for raising and lowering the regulating wheel unit about its pivot and urging the regulating wheel toward and from the grinding wheel to vary the grinding throat, and means for vertically adjusting the depth of the plunger thereby varying the width of the grinding throat between the grinding and regulating wheels.

3. A centerless grinder, including a pair of opposed grinding and regulating wheels forming a grinding throat therebetween, a work rest blade in the grinding throat for supporting a work piece while it is being ground, means for rotating the grinding wheel at a high or rapid rate of speed with its surface adjacent the work rest blade traveling in a downward direction and for rotating the regulating wheel at a slow work controlling rate of speed with its surface adjacent the work rest blade traveling in an upward direction, means pivotally supporting the regulating wheel, means for oscillating the regulating wheel through a predetermined zone for forcing the work piece into the grinding wheel and reducing said work piece to a predetermined size, and means for changing the zone of oscillations of the regulating wheel.

4. A centerless grinder, including a pair of opposed grinding and regulating wheels

forming a grinding throat therebetween, a work rest blade in the grinding throat for supporting a work piece while it is being ground, means for rotating the grinding wheel at a high or rapid rate of speed with its surface adjacent the work rest blade traveling in a downward direction and for rotating the regulating wheel at a slow work controlling rate of speed with its surface adjacent the work rest blade traveling in an upward direction, means pivotally supporting the regulating wheel, means for oscillating the regulating wheel through a predetermined zone for forcing the work piece into the grinding wheel including a positively rotated cam, and means for changing the zone of oscillations of the regulating wheel.

5. A centerless grinder, including a pair of opposed grinding and regulating wheels forming a grinding throat therebetween, a work rest blade in the grinding throat for supporting a work piece while it is being ground, means for rotating the grinding wheel at a high or rapid rate of speed with its surface adjacent the work rest blade traveling in a downward direction and for rotating the regulating wheel at a slow work controlling rate of speed with its surface adjacent the work rest blade traveling in an upward direction, a removable cam for oscillating the regulating wheel unit of given amplitude through a predetermined zone, means for removably operatively mounting the cam whereby interchangeable cams may be utilized for varying the amplitude of oscillations of the regulating wheel unit, and means for varying the zone of oscillations.

6. A centerless grinder including a pair of opposed grinding and regulating wheels forming a grinding throat therebetween, a work rest blade within the throat for supporting a work piece while it is being ground, the wheels being rotated at respectively a high or grinding rate of speed and a slow work controlling rate of speed with their adjacent operative surfaces traveling in opposite directions, a pivoted support for one of the said wheels forming substantially a bell crank lever having the pivot at substantially the apex of the lever, a positively rotated cam for oscillating the housing about the pivotal mounting in the direction of rotation of the wheels, an adjustable follower carried by the housing engaging the cam whereby the oscillations of the wheel may be varied in a vertical plane, and means for adjusting the center of oscillation for changing the zone of oscillations thereabout.

7. In a centerless grinder the combination of a bed or support, a grinding wheel rotatably carried thereby, a slide supported by the bed for movement toward and from the grinding wheel, a regulating wheel unit piv-

oted on the slide, a regulating wheel carried by the unit, and means for oscillating the unit about its pivotal support toward the grinding wheel including an operating cam 5 for positively and definitely effecting and controlling the movement of the regulating wheel in the direction of the grinding wheel for controlling the rate and amount of stock removal from the work and the final size 10 thereof.

8. In a centerless grinder the combination of a bed, a pair of opposed grinding and regulating wheels forming a grinding throat therebetween, a work rest blade within the 15 grinding throat, a housing for the regulating wheel, means pivotally mounting the housing and regulating wheel adjacent the plane of the grinding throat, and cam means for effecting oscillation of the regulating wheel 20 housing and wheel about the pivot in a radial direction relative to and toward the grinding wheel.

9. In a centerless grinder the combination of a bed, a pair of opposed grinding and regulating wheels forming a grinding throat therebetween, a work rest blade within the 25 grinding throat, a housing for the regulating wheel, means pivotally mounting the housing and regulating wheel adjacent the plane 30 of the grinding throat, cam means for effecting oscillation of the regulating wheel housing and wheel about the pivot in a radial direction relative to and toward the grinding wheel, and additional means for adjusting 35 the regulating wheel housing pivot radially of the grinding wheel to vary the zone of oscillation of the regulating wheel.

10. In a centerless grinder the combination of a bed, a grinding wheel rotatably 40 carried thereby, a work support adjacent the active face of the grinding wheel for supporting a work piece during the grinding operation thereon, a work rotation controlling member for engagement with the work 45 piece to control its rotation during the grinding operation, the opposed portions of the grinding wheel and the work rotation controlling member being spaced from one another to form a grinding throat there- 50 between in which is positioned the work support and work, a support for the regulating wheel, means pivotally mounting the support at a point adjacent the plane of the grinding throat, a cam follower carried by 55 the support and a cam for engagement with the follower for oscillating the support and work rotation controlling member about the pivot of the support in a radial direction toward the grinding wheel and for controlling 60 the rate of stock removal from the work piece and the final size thereof.

11. In a centerless grinder the combination of a bed, a grinding wheel rotatably carried thereby, a work support adjacent the 65 active face of the grinding wheel for sup-

porting a work piece during the grinding operation thereon, a work rotation controlling member for engagement with the work piece to control its rotation during the grinding operation, the opposed portions of the grinding wheel and the work rotation controlling member being spaced from one another to form a grinding throat therebetween in which is positioned the work support and work, a support for the regulating wheel, means pivotally mounting the support at a point adjacent the plane of the grinding throat, a cam follower carried by the support and a cam for engagement with the follower for oscillating the support and work rotation controlling member about the pivot of the support in a radial direction toward the grinding wheel and for controlling the rate of stock removal from the work piece and the final size thereof, and means for adjusting the follower relative to the support and cam to change the zone through which the oscillations of the support takes place.

12. In a centerless grinder the combination of a bed, a grinding wheel rotatably carried thereby, a work support adjacent the active face of the grinding wheel for supporting a work piece during the grinding operation thereon, a work rotation controlling member for engagement with the work piece to control its rotation during the grinding operation, the opposed portions of the grinding wheel and the work rotation controlling member being spaced from one another to form a grinding throat therebetween in which is positioned the work support and work, a support for the regulating wheel, a slide carried by the bed for movement toward and from the grinding wheel, means pivotally mounting the support to the slide at a point adjacent the grinding throat, a cam follower carried by the support, a cam for engagement with the follower for oscillating the support and work rotation controlling member about the pivot of the support in a radial direction toward the grinding wheel and for controlling the rate of stock removal from the work and the final size thereof, means for adjusting the follower relative to the support and cam to change the zone through which the oscillations of the support take place, and additional means for adjusting the slide radially of the grinding wheel to vary the position of the support pivot with respect to the grinding throat.

In testimony whereof I affix my signature.
JOHN E. CASTER.
